UNITED STATES PATENT OFFICE.

BRUCE FORD, OF PHILADELPHIA, PENNSYLVANIA.

HANDLE FOR BATTERY-BOXES AND MEANS FOR LOCKING SAME.

1,238,753.

Specification of Letters Patent.

Patented Sept. 4, 1917.

Application filed April 19, 1913. Serial No. 762,194.

To all whom it may concern:

Be it known that I, BRUCE FORD, a citizen of the United States, and a resident of Philadelphia, in the county of Philadelphia 5 and State of Pennsylvania, have invented a certain new and useful Handle for Battery-Boxes and Means for Locking Same, of which the following is a specification.

The principal object of the present invention is to provide a readily accessible handle for battery boxes and to secure the same to the wall of the battery box in such manner that as the box is dragged lengthwise the strain on the handle is resisted by 15 the full thickness of the end of the box.

The invention will be claimed at the end hereof, but will be first described in connection with the embodiment chosen for illustration in the accompanying drawings, 20 in which—

Figure 1, is an elevational view of a portion of the outside of a battery box equipped with a handle embodying features of the invention.

Fig. 2, is a transverse sectional view of the same.

Figs. 3, 4, and 5, are detail views illustrating parts of the locking means, and

Figs. 6 and 7, are respectively a sectional 30 and a side view of a modification.

In the drawings 1 is the wall of a battery box. It is provided with a lengthwise opening 2 and a crosswise opening 3. 4, is a socket adapted to be arranged in the opening 3 in the side wall of the box and it is provided with a threaded end 5 and with a transverse opening 6. 7, is a notch for gauging the alignment of the hole in assembling the parts. 8, is a nut having the 40 general form of a conic frustum, and adapted to engage the thread 5 and to occupy an appropriately shaped seat formed in the side wall 1. 9, is a lock washer arranged on the inner face of the nut, when necessary. The bail part 10 of the handle may be offset inward from the outer edge of the box. Each arm 11 of the handle extends into a recess 2 and as shown is notched 50 at 12 for the reception of the cylindrical part 13 of the socket.

The parts may be assembled by first inserting the socket through the opening 3 and then applying the nut and lock washer loosely to its threaded end. The arm 11 can then be inserted in the cavity 2 through the opening 6 to its proper position, or until the notch 12 is opposite the part 13 of the socket. Thereupon the nut can be screwed up, for example, by means of a spanner applied to the groove 14 and it will then hold 60 the handle firmly in place. The arms or end parts of the handles are clamped from the inside face of the wall of the box, so that the strength of the thickness of that wall is utilized for resisting dragging pulls 65 on the handle. By putting the ends of the handles in the openings 2, both the inside and outside of the box are smooth, but the handles may be on the outside as in Fig. 6, and the socket may be provided with a lateral hole or opening 6^a, Fig. 7.

What I claim is new and desire to secure by Letters Patent is:

1. In a box the combination of a box wall, a handle having two straight arms parallel 75 with the wall, and a pair of threaded co-operating socket and nut-members arranged through the wall and whereof the socket member of each pair is provided with an opening through which one handle arm 80 passes and is movable in respect to the box wall to clamp the arm in respect to the box wall and the wall of the opening.

2. In a box the combination of an integral box-wall having vertical openings in 85 it arranged between its inside and outside faces, a handle having a bail above the top of the box and having two arms arranged in said openings, and threaded nuts and co-operating sockets arranged through the 90 wall of the box, said sockets having openings the walls of which clamp the arms in respect to the box wall, substantially as described.

In testimony whereof I have hereunto 95 signed my name.

BRUCE FORD.
